UNITED STATES PATENT OFFICE.

CHARLES E. POPE, OF HOLYOKE, MASSACHUSETTS.

BROOM-HOLDER.

SPECIFICATION forming part of Letters Patent No. 765,633, dated July 19, 1904.

Application filed January 29, 1904. Serial No. 191,079. (No model.)

To all whom it may concern:

Be it known that I, CHARLES E. POPE, a citizen of the United States of America, and a resident of Holyoke, in the county of Hampden 5 and State of Massachusetts, have invented certain new and useful Improvements in Broom-Holders, of which the following is a full, clear, and exact description.

This invention relates to an improved holder 10 for brooms, tools, or other objects, and has for its purpose the provision of a holder which is of the utmost simplicity of construction and efficiency and convenience of operation.

The invention consists in parts formed and 15 combined substantially as hereinafter fully described, and set forth in the claim.

Referring to the accompanying drawings, Figure 1 is a perspective view of the improved holder illustrated as in use for the retention 20 of a broom. Fig. 2 is an enlarged front elevation of the holder. Fig. 3 is a horizontal sectional view as taken on the line 3-3, Fig. 2.

Similar characters of reference indicate corresponding parts in all of the views.

The device is constituted by a metallic support or holder A, which may be of flat sheet metal having an end portion thereof forwardly bent to constitute an abutment a, such abutment having a curved form to conform more 30 or less to the cylindrical shape of a broom or tool handle.

B represents a pawl which in the present instance is shown as constituted by a flat strip of sufficiently rigid metal having an extremity 35 thereof looped to constitute an eye, as represented at b, while the end of this pawl opposite the loop end is of concave form, as represented at d, also to conform more or less nearly to the cylindrical shape of the broom- 40 handle. The pawl is pivotally connected at its eye-formed end on the holder at the end thereof opposite from the abutment a.

As particularly represented in Fig. 3, a compound pivot-forming and holder-fastening 45 provision is represented as constituted by the part comprising the slotted head 10, the cylindrical shank portion 12, which has its position within the loop or eye of the pawl, and the attenuated screw-shank 13, which enters

through and beyond an aperture 14 in the 50 holder-plate, screwing into the woodwork, which makes any suitable support in which the device is mounted.

It will be observed that the length of the cylindrical unthreaded portion 12 is slightly 55 longer than the distance through the eye of the pawl, the shoulder 15 coming to a seat against the face of the plate, as drawn there- to by the screw action of the extremity 13, while the head 10 prevents the pawl from dis- 60 placement.

The plate has the bottom forwardly-projecting lip f (shown in dotted lines in Fig. 3) and the top forwardly-projecting lip g, the former supporting the pawl from falling below its normal position, (represented in Fig. 2,) while the upper lip prevents the pawl from being overthrown at a time when the broom may be, perhaps, too forcibly brought into engagement in the holder. 70

In addition to the fastening for the device-head by the threaded extremity 13 of the pivot-stud a screw 16 may be employed, sub-stantially as shown.

In disuse the parts will have the relation 75 represented by full lines in Fig. 2, and when the broom is to be engaged in the holder its upper end is brought against the lower surface of the pawl near its free end and moved upwardly and slid through the space between 80 the upwardly-swung pawl and the abutment a, and then by permitting the broom to have a descending movement the pawl following the broom, by reason of its gravity, will by its end edge engage and bite into the side of the 85 broom-handle and retain the same, as represented in Fig. 1.

The parts manifestly may be cheaply and rapidly constructed and easily assembled, and there is no necessity for nicety in manufac- 90 ture or adjustment of the parts.

Having thus described my invention, what I claim, and desire to secure by Letters Patent, is—

In a device of the character described, a plate 95 having an end portion forwardly bent to constitute an abutment, and having upper and lower forwardly-projecting lips, a pawl com-

posed of a strip of flat metal provided with a loop at one end, a screw having a head, a cylindrical shank next thereto, upon which the loop of the pawl is arranged, and a screw-threaded extremity of smaller diameter than the cylindrical shank extended through an aperture in and beyond the plate, said cylindrical shank forming a shoulder which engages the plate to limit the inward movement

of the screw and prevent binding of the head ¹⁰ on the pawl.

Signed by me at Springfield, Massachusetts,
this 18th day of January, 1904.

CHARLES E. POPE.
